GRINDING MACHINE

George W. Binns and Frederick J. Theler, Cincinnati, Ohio, assignors to The Cincinnati Milling Machine Co., Cincinnati, Ohio, a corporation of Ohio

Application June 10, 1943, Serial No. 490,254

21 Claims. (Cl. 51—74)

This invention relates to grinding machines. One of the objects of this invention is to provide a simple, thoroughly practical, and durable ball grinding machine. Another object is to provide an attachment for a centerless grinding machine which will permit the balls to be economically and accurately ground thereby. Other objects will be in part obvious and in part pointed out hereinafter.

The invention accordingly consists in the features of construction, combinations of elements, and arrangements of parts, all as will be illustratively described herein, and the scope of the application of which will be indicated in the following claims.

In the accompanying drawings in which is shown one of the various possible embodiments of this invention,

Figure 1 is a front elevation of a centerless grinding machine having the ball grinding attachment mounted thereon;

Figure 2 is a side elevation of the ball grinding attachment taken on the line 2—2 of Figure 1;

Figure 3 is a vertical section taken on the line 3—3 of Figure 2;

Figure 4 is a vertical section taken on the line 4—4 of Figure 2;

Figure 5 is a section taken on the line 5—5 of Figure 4;

Figure 6 is a horizontal section taken on the line 6—6 of Figure 5; and,

Figure 7 is a section taken on the line 7—7 of Figure 5.

Similar reference characters refer to similar parts throughout the several views of the drawings.

This invention relates to certain improvement in the method and apparatus disclosed in application Serial No. 470,314, filed December 24, 1942, for a Grinding machine and method of grinding.

Referring now to Figure 1, a standard centerless grinding machine is shown having a grinding wheel 11 and a regulating wheel 12 mounted on a bed 10. Regulating wheel 12 is mounted on a carriage 13 (Figures 1 and 2) which moves longitudinally of the bed 10 on surface ways 14. Carriage 13 is moved on ways 14 by a hand-wheel 15, thus permitting the distance between the grinding and regulating wheels to be adjusted as desired.

The grinding and regulating wheels are provided with suitable truing mechanisms, generally indicated at 16 and 17 respectively, by which the active opposed surfaces of the wheels

are trued. The regulating wheel 12 rotates at a relatively slow speed in a clockwise direction, as viewed in Figure 1, and thus turns the work in the grinding throat between the wheels in a counter-clockwise direction toward the grinding wheel. The grinding wheel rotates at a high speed in a clockwise direction, as viewed in Figure 1, and effects a stock removal from the work.

Referring now to Figures 1 and 2, an attachment, generally indicated at 18, is positioned between the grinding and regulating wheels. This attachment supports and acts upon the work passing through the grinding throat. In general, the attachment includes a framework sup-

porting a reciprocating work rest blade, generally indicated at 19, mechanism for feeding work onto and along the work rest blade 19, and mechanism generally indicated at 20 for driving

the work rest blade 19. The work, such as a train of balls, is fed into the grinding throat adjacent the left-hand edge of the grinding wheel, as viewed in Figure 2, and is moved through the grinding throat from left to right

25 by the cam feeding mechanism, generally indicated at 21. During the time the work is in the grinding throat, it is acted upon or actuated by the regulating wheel, grinding wheel, cam feeding mechanism, and reciprocating work rest

30 blade.

The framework of the attachment includes a bed plate, generally indicated at 22, which is mounted on ways 23 on carriage 13 for longitudinal movement with respect thereto. This 35 permits the attachment, which is positioned in a plane tangent to the surfaces of the grinding and regulating wheels, to be moved toward and from the regulating wheel. A transverse plate, generally indicated at 24 (Figures 2 and 3), is mounted above bed plate 22 by a pair of vertical supports, generally indicated at 25a and 25b.

These supports, which are substantially similar in construction, are bolted to transverse plate 24 and bed plate 22, and curve rearwardly (Figure 3) so that they are out of the path of a reciprocating shuttle member, generally indicated at 26 (Figures 2 and 3), carrying work rest blade 19.

Shuttle member 26 (Figures 2 and 3) is in the 40 form of a flat plate vertically positioned between transverse plate 24 and bed plate 22. This plate 26 (Figure 2) extends a substantial distance below the top edge 22a (Figures 2 and 4) of bed plate 22 as indicated by the dotted line 26a and 45 lies in a cut-out portion 22b (Figure 4) of bed

plate 22. Reciprocating shuttle member 26 (Figures 2 and 3) has beveled edges 30a, 30b, 30c, and 30d formed on the upper and lower edges thereof adjacent its left and right-hand ends, as viewed in Figure 2. These beveled edges fit the grooves in the rollers of roller assemblies, generally indicated at 31a, 31b, 31c, and 31d, which permit movement of the reciprocating shuttle member transversely with respect to the faces of the grinding and regulating wheels.

As roller assemblies 31a and 31b are substantially similar to roller assemblies 31c and 31d respectively, detailed description will be limited to roller assemblies 31a and 31b. Roller assembly 31a is pivotally mounted on vertical support 25a by a stud shaft 32 (Figure 3). An arm 33 extends to the right (Figure 2) from shaft 32 and carries a roller 34 on its right-hand end. Arm 33 is resiliently urged downwardly by a spring 35 connected to bolt 36, which in turn is connected to bed plate 22. The degree of tension of spring 35 may be adjusted by means of nuts 37. Adjustable stops, generally indicated at 38a and 38b, are provided, which coact with a lug 39 on arm 33 to limit upward and downward movement of the arm.

Roller assembly 30b includes an arm 40 (Figures 2 and 3) pivotally mounted by a stud shaft 41 on the lower end of vertical support 25a. The right-hand end of arm 40, as viewed in Figure 2, carries a roller 42, which is rotatably mounted thereon by a stud shaft 43. Roller 42 may be adjusted vertically with respect to bed plate 22 by means of a stop 44 which threads through bed plate 22 and contacts the under side of arm 40 (Figure 2). Thus the position of the roller assemblies may be adjusted with respect to the bed plate and through this adjustment, the reciprocating shuttle member which rides on the rollers may be vertically adjusted with respect to the grinding throat of the machine.

The reciprocating shuttle member 26 has a cut-out portion 26b (Figure 2) in the center portion thereof positioned below the grinding throat. The work rest blade 19 (Figure 2) is connected to reciprocating shuttle member 26 by bolts 48, which extend through the shuttle member 26. The upper edge 19a of the work rest blade is beveled toward the regulating wheel (Figure 4) and thus the work resting upon this edge is urged by the force of gravity into contact with the regulating wheel. To prevent work from jumping up out of the grinding throat during the grinding operation, a retainer blade 50 (Figures 2 and 4) is provided. This retaining blade is connected to transverse plate 24 by bolts 51 and its lower edge is positioned immediately above the balls in the grinding throat (Figure 4). Bolts 51 extend through slots in the retainer blade and thus vertical adjustment of both the work rest blade and the retainer blade with respect to the grinding throat is permitted. The shuttle member and thus blade 19 is driven by hydraulic mechanism 20 through a rod 80 connected to shuttle member 26 by swivel joint 81. This hydraulic mechanism which reciprocates shuttle member 26 may be similar to the hydraulic mechanism described in the application referred to hereinabove although other mechanism may be used for this purpose.

A third vertical support 52 (Figure 2) substantially similar in construction to supports 25a and 25b is positioned adjacent the left-hand edge of the grinding wheel, as viewed in Figure 2. A motor 55 is secured to transverse plate 24 by a bracket 56 (Figure 3) in front of vertical support

52 (Figure 2). The shaft 57 of this motor has a cam 58 (Figures 2, 4, and 6) connected to its lower end. The motor, cam, and shaft are preferably diagonally positioned with respect to the plane in which the attachment lies to permit cam 58 to lie in a plane parallel to the beveled edge 19a of the work rest blade 19 (Figure 4). Cam 58 is driven by the motor in the direction of the arrow in Figure 6, and each time it makes 10 a revolution, it moves the train of balls on the work rest blade from left to right, as viewed in Figure 2, the width of one ball.

A feeding tube 62 (Figures 2 and 4) is also connected to motor 55 by brackets 62a. This tube is preferably parallel to the shaft 57 of motor 55, and the balls may be fed into this tube in any suitable manner, such as by a hopper. The lower end of this tube opens immediately above the beveled edge 19a (Figures 4 and 5) of the work rest blade 19, and a channel portion 62a (Figures 2, 5 and 7) formed on the feeding tube 62 extends from the lower end of the feeding tube to a point adjacent the left-hand end of the grinding throat, as viewed in Figure 2. This 20 channel portion holds the balls on the edge of the work rest blade as they are being fed into the grinding throat.

Immediately above cam 58 a second cam 80 (Figures 2 and 5) is mounted on shaft 57 between 30 collars 57a and 57b (Figure 5). Cam 80 acting through pin 91 actuates a latch member 60 mounted for transverse movement with respect to shaft 57. Cam 80 moves latch member 60 to the left as viewed in Figures 2 and 5 and spring 35 means (not shown) moves the latch member to the right. Latch member 60 extends through a hole 61 in the lower portion of feeding tube 62, and as shaft 57 rotates, latch 60 is withdrawn from its blocking position in the feeding tube 40 each time cam 58 makes a revolution. In operation, the balls are fed into the feeding tube and fall downwardly therein until they strike latch member 60 (Figure 5). On each revolution of the feeding cam 58, latch member 60 is withdrawn to permit a ball to drop into the space provided on the edge of the work rest blade by the revolution of the cam 58. Suitable means are preferably provided for regulating the speed of motor 55 and thus the revolutions per minute of cam 58 so that the rate of feed at which balls are fed through the grinding throat may be varied.

As the balls are fed through the grinding throat by cam 58, they are acted upon by the reciprocating work rest blade, the regulating wheel, and the grinding wheel. The reciprocating work rest blade rotates the balls in directions transverse to the direction of rotation of the grinding wheel or about axes at right angles to the axis of the 55 grinding wheel while the regulating wheel rotates the balls in a direction toward the grinding wheel or on axes substantially parallel to the grinding wheel. In addition, the balls are being positively fed in one direction at a uniform rate 60 by the feeding cam 58 with the result that when the reciprocating support is moving in the direction of feed it imparts a slow rate of rotation to the balls in one direction, but as it returns it imparts a faster rate of rotation to the balls but 65 in an opposite direction. As these forces (work rest blade 19, regulating wheel 12 and cam 58) act simultaneously to turn the balls in different directions, the balls continually present different surfaces to the grinding wheel, stock being removed from the balls in the lines of innumerable 70 75

great circles. Because of this action, all points on the surface of each ball are presented to the grinding wheel as each ball passes through the grinding throat. As the balls pass from the grinding throat, the ball at the right-hand end of the train, as viewed in Figure 2, falls off of the beveled edge 19a of the work rest blade 19 into a hopper (not shown) and passes from the machine.

It will thus be seen that thoroughly efficient apparatus for grinding balls on a centerless grinder has been provided. By the use of this apparatus, balls may be efficiently, quickly, and accurately ground.

Thus, the several objects mentioned hereinabove, as well as many others, are successfully and practically accomplished by the method and apparatus disclosed hereinabove.

As many possible embodiments may be made of the mechanical features of the above invention, all without departing from the scope of the invention, it is to be understood that all matter hereinabove set forth, or shown in the accompanying drawings, is to be interpreted as illustrative and not in a limiting sense.

We claim:

1. In apparatus of the nature described, in combination, a grinding wheel and a regulating wheel forming a grinding throat therebetween, work rest means for supporting a train of balls in said grinding throat, said regulating wheel causing rotation of said balls in the direction of said grinding wheel, and means for continuously moving said work rest means with a reciprocating action transverse to the faces of said wheels, said reciprocating work rest means causing rotation of said balls in directions transverse to the direction of rotation of said wheels throughout the period said balls are in said grinding throat.

2. In apparatus of the nature described, in combination, a grinding wheel, a regulating wheel for rotating a train of balls in the grinding throat formed between the grinding and regulating wheels in a direction toward the grinding wheel, said grinding and regulating wheels having plain operative faces, work rest means for supporting said balls in said grinding throat, means for feeding balls into said grinding throat, and means for continuously moving said work rest means with a reciprocating action transverse to the faces of said wheels.

3. In apparatus of the nature described, in combination, a grinding wheel and a regulating wheel forming a grinding throat, said grinding and regulating wheels having plain operative faces, work rest means having a straight work supporting edge for supporting a train of balls in said grinding throat, means for moving said work rest means with a reciprocating action transverse to the faces of said wheels, and means for feeding balls into said grinding throat and for causing said balls to pass through said grinding throat, said balls passing through said grinding throat on the straight work supporting edge of said work rest means.

4. In apparatus of the nature described, in combination, a grinding wheel, a regulating wheel for rotating a train of balls in the grinding throat formed between the grinding and regulating wheels in a direction toward the grinding wheel, the operative faces of each of said wheels being substantially parallel to their axes of rotation, and a reciprocating work rest blade for supporting said train of balls in said grinding throat,

said work rest blade moving transversely to the faces of said wheels.

5. In apparatus of the nature described, in combination, a grinding wheel and a regulating wheel forming a grinding throat therebetween, work rest means having a substantially straight work supporting edge extending through said grinding throat for supporting a train of balls, said work rest means moving transversely of the faces of said wheels, and reciprocating means acting through said work rest means for causing said balls to rotate transverse to the direction of rotation imparted to said balls by said regulating wheel.

10 6. In apparatus of the nature described, in combination, a grinding wheel and a regulating wheel forming a grinding throat therebetween, work rest means, reciprocating means acting through said work rest means for causing said balls to rotate in both directions alternately transverse to the direction of rotation imparted to said balls by said regulating wheel, and cam feeding means for feeding balls one at a time onto said work rest means.

15 7. In apparatus of the nature described, in combination, a grinding wheel and a regulating wheel forming a grinding throat therebetween, a reciprocating work rest means for supporting a train of balls in said grinding throat, and cam feeding means for feeding balls into and through said grinding throat.

20 8. In apparatus of the nature described, in combination, a grinding wheel and a regulating wheel forming a grinding throat therebetween, a reciprocating work rest means for supporting a train of balls in said grinding throat, cam feeding means for feeding balls into and through said grinding throat, and means positioned above the balls in said grinding throat for preventing the 25 balls from moving upwardly out of said grinding throat.

30 9. In apparatus of the nature described, in combination, a grinding wheel and a regulating wheel forming a grinding throat therebetween, reciprocating work rest means for supporting a train of balls in said grinding throat and rotating said balls in directions transverse to the direction 35 of rotation of said wheels, means for feeding balls into said grinding throat, and means for controlling the rate at which balls are fed into said grinding throat.

40 10. In apparatus of the nature described, in combination, a grinding wheel and a regulating wheel forming a grinding throat therebetween, reciprocating work rest means for supporting a train of balls in said grinding throat and for rotating said balls in directions transverse to the direction of rotation of said wheels, cam means for feeding said balls into and through said grinding throat, and means for controlling the rate at 45 which said cam means feeds balls into said grinding throat.

11. In apparatus of the nature described, in combination, a grinding wheel and a regulating wheel forming a grinding throat therebetween, work rest means for supporting a train of balls in said grinding throat, and rotating cam means acting directly upon one end of said train of balls for feeding said train of balls into and through 50 said grinding throat.

12. In apparatus of the nature described, in combination, a grinding wheel and a regulating wheel forming a grinding throat therebetween, work rest means for supporting a train of balls in said grinding throat, rotating cam means act-

ing directly upon one end of said train of balls for feeding said train of balls into and through said grinding throat, means for feeding balls onto said work rest means adjacent said cam means, and latch means permitting only one ball to be fed onto said work rest means each time said cam means rotates.

13. In apparatus of the nature described, in combination, a grinding wheel and a regulating wheel forming a grinding throat therebetween, reciprocating work rest means for supporting a train of balls in said grinding throat, rotating cam means acting directly upon one end of said train of balls for feeding said train of balls into and through said grinding throat, means for feeding balls onto said work rest means adjacent said cam means, and latch means permitting only one ball to be fed onto said work rest means each time said cam means rotates.

14. In apparatus of the nature described, in combination, a grinding wheel and a regulating wheel forming a grinding throat therebetween, said wheels having substantially parallel operative faces, a reciprocating shuttle member, work rest means having a substantially straight work supporting edge mounted on said shuttle member for supporting a train of balls in said grinding throat, said work rest means moving transversely of the faces of said wheels, and means for feeding balls into said grinding throat.

15. In apparatus of the nature described, in combination, a grinding wheel and a regulating wheel forming a grinding throat therebetween, a reciprocating shuttle member, work rest means mounted on said shuttle member for supporting a train of balls in said grinding throat, means for feeding balls into said grinding throat, and means permitting adjustment of said work rest means with respect to said grinding throat.

16. In apparatus of the nature described, in combination, a grinding wheel and a regulating wheel forming a grinding throat therebetween, a reciprocating shuttle member moving transverse to the direction of rotation of said grinding wheels, a work rest means for supporting a train of balls in said grinding throat mounted on said shuttle member, cam feeding means for feeding balls into and through said grinding throat, and means for preventing balls from moving upwardly out of said grinding throat.

17. In apparatus of the nature described, in combination, a grinding wheel and a regulating wheel forming a grinding throat therebetween, work rest means for supporting a train of balls in said grinding throat, means acting through said work rest means for rotating the balls in said train of balls in directions transverse to the faces

of said grinding and regulating wheels, and means for preventing movement of said balls transversely of said grinding and regulating wheels during the rotation of said balls.

5 18. In apparatus of the nature described, in combination, a grinding wheel and a regulating wheel forming a grinding throat, reciprocating work rest means for supporting a train of balls in said grinding throat, said reciprocating work rest means rotating the balls in said train of balls in directions transverse to the faces of said grinding and regulating wheels as it reciprocates, and means for preventing movement of said balls transversely of said grinding and regulating wheels during the rotation of said balls.

10 19. In apparatus of the nature described, in combination, a grinding wheel and a regulating wheel forming a grinding throat therebetween, work rest means for supporting a train of balls in said grinding throat, means acting through said work rest means for rotating the balls in said train of balls in directions transverse to the faces of said grinding and regulating wheels, means to feed said balls through said grinding throat, and means for preventing movement of said balls transversely of said grinding and regulating wheels with the exception of said feeding movement during the rotation of said balls.

20 25 20. In apparatus of the nature described, in combination, a grinding wheel and a regulating wheel forming a grinding throat, said wheels having substantially parallel operative faces, the operative face of each wheel being substantially parallel to the axis of its wheel, reciprocating work rest means for supporting a train of balls in said grinding throat, said work rest means as it reciprocates rotating the balls in said train of balls in directions transverse to the faces of said grinding and regulating wheels, and means preventing reciprocation of said balls with said work rest means as said work rest means reciprocates.

30 35 40 45 50 55 21. In apparatus of the nature described, in combination, a grinding wheel and a regulating wheel forming a grinding throat therebetween, a reciprocating shuttle member moving substantially parallel to the axes of said grinding and regulating wheels, a work rest blade mounted on said reciprocating shuttle member for supporting a train of balls in said grinding throat, and means for preventing reciprocating movement of said balls as said work rest blade reciprocates, said work rest blade causing rotation of said balls in directions transverse to the faces of said grinding and regulating wheels.

GEORGE W. BINNS.
FREDERICK J. THELER.
